METHOD OF WATERPROOFING PLASTER

Arthur K. Laukel, Detroit, Mich.

No Drawing. Application July 29, 1932,
Serial No. 625,659

5 Claims. (Cl. 91—68)

In the preparation of a plaster of Paris object for electro-plating on one or all of its surfaces, it is necessary to render the object water-proof so that it may be suspended in the plating bath 5 without injury. This is commonly done by immersing the object in molten wax after drying. Occasionally the wax fails to penetrate certain areas of the surface of the object, and the present invention deals with the elimination of this 10 difficulty.

It is believed that in oven drying of the plaster, before waterproofing, soluble salts are brought to the surface thereof and crystallized, forming a coating which resists penetration by the wax. 15 The compounds in the plaster form the aforementioned salts on the surface, and resist absorption of the wax.

According to the invention, an impervious formation of these salts is avoided by treating the 20 surface of the plaster with an oily, greasy or non-volatile fluid or dissolved wax before drying. The surface of the plaster is coated with a grease, wax solution, oil (mineral or vegetable), or a non-volatile material such as glycerine. It 25 is preferred to use a substance which is soluble in the water-proofing material, such as mineral oil or petrolatum. The coating may be applied by dipping, spraying or brushing.

A surface thus treated does not dry out rapidly, 30 and crystallization is thereby retarded. The usual tendency of the surface to dry out while the interior is wet is avoided, and hence there is no interruption of the evaporation stream. The oven may be heated higher than usual, with 35 a rapid but gradual drying and without the sudden drying of the surface that would otherwise occur.

In a preferred embodiment of the invention, hot molten petrolatum is used. This is not absorbed at once into the surface of the plaster 40 and remains longer on the surface during drying.

The invention is not limited to any of the materials specifically named but rather includes

any non-volatile or slowly volatile material adapted to penetrate the surface of plaster and prevent the impervious formation of salts therein or thereon.

Having thus fully described my invention, I claim:

1. In the drying of a plaster object preparatory to water-proofing, the operation of treating the surface of the plaster, before drying, with a material adapted to prevent impervious crystallization of salts at said surface and subsequently subjecting said object to a drying operation, and finally impregnating said surface with a water-proofing material after drying. 65

2. In the drying of a plaster object preparatory to water-proofing, the operation of treating the surface of the plaster, before drying, with an oily or a greasy material and subsequently subjecting said object to a drying operation, and finally impregnating said surface with a water- 70 proofing material after drying. 75

3. In a water-proofing of plaster objects, the method consisting in treating the surface of the plaster object, before drying, with an oily or greasy material, drying the object, and impregnating said surface with a water-proofing material in which the first material is soluble. 80

4. In the water-proofing of plaster objects, the method consisting in treating the surface of the plaster object, before drying, with an oily or greasy material adapted to be absorbed in the plaster and less volatile than water, drying the object, and impregnating said surface with a water-proofing in which the first material is soluble. 85

5. In the drying of a plaster object preparatory to water-proofing, the operation of penetrating the surface of the plaster, before drying, with petrolatum, subsequently subjecting said object to a drying operation, and impregnating 95 said surface with a water-proof material in which petrolatum is soluble.

ARTHUR K. LAUKEL.
